KNIFE SHARPENER

Charles B. Rosenberg, Royal Oak, Mich.
Application May 4, 1955, Serial No. 35,801

Term of patent 14 years
(Cl. D37—1)

Figure 1 is a top plan view of a knife sharpener embodying my new design;

Figure 2 is a side elevation view;

Figure 3 is an end elevation view; and

Figure 4 is a sectional view taken along line 4—4 of Fig. 2.

I claim:

The ornamental design for a knife sharpener, as shown.
